UNITED STATES PATENT OFFICE.

WILLIAM J. EDWARDS AND WILLIAM M. WAUTERS, OF BAYONNE, NEW JERSEY.

DOWELING-MACHINE.

SPECIFICATION forming part of Letters Patent No. 705,657, dated July 29, 1902.

Application filed March 14, 1902. Serial No. 98,170. (No model.)

To all whom it may concern:

Be it known that we, WILLIAM J. EDWARDS and WILLIAM M. WAUTERS, citizens of the United States, residing at Bayonne, county of 5 Hudson, State of New Jersey, have jointly invented a certain new and Improved Doweling-Machine, of which the following is a specification.

This invention is primarily intended for use 10 in the manufacture of wooden boxes and barrels, but is applicable to other uses; and its object is to provide a machine by which the sections of a barrel-head or two pieces of board designed to form an end or side of a 15 box may be securely united by dowels.

The form in which we have elected to disclose our invention is that of a machine for doweling sections of box ends or sides. Experience has demonstrated that this embodiment of the invention is a practical and efficient one, and it is the form now best known to us. Nevertheless the invention may be embodied in other forms, and some features may be used without others and in machines 25 otherwise differing from that herein shown.

In the accompanying drawings, Figure 1 is a side elevation; Fig. 2, an end elevation; Fig. 3, a plan, on an enlarged scale, with some of the parts broken away and some omitted; 30 Fig. 4, a view, on the same scale as Fig. 3, of the upper part of the machine, partly in side elevation and partly in section, on the lines 4 4 and 4' 4'; Fig. 5, a detail view on an enlarged scale, showing part of the main crank- 35 shaft and the connection for actuating the sliding head that forces the boards together. Figs. 6, 7, 8, 9, 10, 11, and 12 are detail views of different parts of the machine; Fig. 13, a detail section showing the dowel-hopper and 40 one of the channeled arms in which it is pivoted; Fig. 14, a plan view of the hopper; Fig. 15, a section on the line 15 15 of Fig. 14; Fig. 16, a section on the line 16 16 of Fig. 14; Fig. 17, a section on the line 17 17 of Fig. 14. 45 Figs. 18, 19, and 20 are diagram views illustrating the doweling of two boards, and Fig. 21 a detail sectional view showing two boards united by dowels and lying between the dowel-holders.

50 The various movements of the machine have been shown as accomplished by devices

ordinarily employed by mechanicians, although in some minor features there may be novelty in details of structure.

In this machine two pieces, which together 55 form a symmetrical part or whole of a box side or end or barrel-top and the abutting edges of which have preferably been drilled previously in any suitable way to receive the dowels or securing-pieces, are placed upon 60 the bed of the machine on opposite sides of appropriately-located dowel-holders. Then while appropriately held the edges of the pieces are forced together and upon the dowels which unite them, however irregular 65 or whatever may be the angular position of the joint. The dowel-holders are automatically supplied with dowels for the next pair of pieces to be united, and the dowels are automatically fed for this purpose from a 70 hopper.

The bed-plate A of the machine is appropriately supported by any suitable frame, and on one end thereof is mounted a sliding head B, which receives its motion from a rocking-head arm B', as hereinafter described. That part of the bed-plate to the right of the sliding head forms the table upon which the pieces to be united are placed, and at the rear edge thereof a suitable gage or stop-plate A' 80 is mounted. On opposite sides of this part of the bed-plate are mounted sliding dowel-holder frames, each constructed as follows: There is an angled plate C, constituting the slide and formed with or carrying a yoke C', 85 which, Fig. 3, first extends outwardly, then to the right parallel with the bed-plate, then upwardly and to the left, overlying its lower part, and the two ends of the yoke terminate opposite each other, being formed with hubs 90 or tubular parts C², whose axes are vertical and coincident. These hubs carry opposed dowel-holders or clamps D, having stems d, fitted to slide in the hubs and guided by pins d', working in slots therein, and are urged 95 toward each other yieldingly by springs contained within the hubs, and the upper one of which is shown in Fig. 4. The right and left hand edges of the dowel-holders are beveled inwardly, Figs. 1 and 21, and their contiguous faces are formed with opposite grooves d³, 100 parallel with the line of reciprocation of the

slide B and in which the double - pointed dowels Z are held and clamped. A pin c projects from the inner face of each dowel-frame slide C through an elongated slot c' in the vertical wall of the bed-plate and is engaged by the forked end of a rocking arm E, loosely mounted on a rock-shaft E' and connected by a coiled spring B² with the rocking arm B', that actuates the sliding head. The mode of operating the arms E is hereinafter described. At the moment it is sufficient to know that they may rock independently on their shaft E' and also that they can be positively moved together to the right for the following purpose: At the right-hand end of the table and on each side thereof, opposite the dowel-holders, is mounted a radial receptacle F, to which the dowels are automatically fed, as hereinafter described, and from the bottom of which, through an aperture in the projecting edge or base f of the receptacle, dowels are at the proper time, by means of an automatically-actuated plunger f', forced out of the receptacle and into position between the dowel-holders D, as indicated, for instance, in Fig. 4. The lever G, pivoted at G' at the extreme right of the bed-plate, extends to the left over the bed-plate and has pivotally mounted in its end a presser-plate G² for bearing upon and holding the pieces of board deposited upon the bed-plate. A spring G³, Figs. 1 and 6, tends normally to draw the arm downwardly and is permitted to do so at the proper time, as hereinafter described.

We will first describe the operation of doweling two pieces and then the mechanism by which the parts of the machine thus far referred to are actuated.

The dowel-holders D being in the position indicated in Fig. 1 and dowels Z being clamped between them two pieces of board Y Y, the edges of which, preferably, as indicated at y, have been drilled, are laid upon the table A on opposite sides of the dowel-holders. The presser-plate G², the leading edge of which is above or turned upwardly, descends. The sliding head B advances, carrying the adjacent board Y with it and presenting its edge or the drilled holes therein to the dowels held in the holders D. If this edge of the board is of irregular contour or is at an angle other than ninety degrees to the front and rear edges of the board, one of the dowel-holders will be pushed ahead of the other until finally the edges of both pieces of the board are forced against the dowels in the two holders. As the slide advances and the dowels enter the apertures in the edges of the boards the holders D D, being beveled, are forced apart by the strain, and the opposite edges of the board are pressed together. At this time the projecting edge or base f of the dowel-receptacles forms an abutment against which the pressure is exerted. The operation is shown in Figs. 18 to 21, inclusive. The slide B recedes, the presser G² rises, and the operator now withdraws the united boards

from between the dowel-holders D, and these holders are then positively advanced to the position indicated in Fig. 4, when the plungers f' are operated and dowels are again forced into position between them. During this action the presser-plate G² has been raised and the sliding head B has been retracted. The dowel-holders, each carrying a new dowel, are now returned to the initial position (indicated in Fig. 1) and the operator may place upon the table A another pair of boards to be united. We prefer that the machine should come to rest in the initial or normal position shown in Fig. 1 and be set into operation at the will of the operator to perform the general operations described, and we have accordingly so shown it.

At one end of the frame is a driving-shaft 1, having at one end a pulley 2, driven by a belt 3, and at the other end, keyed to it, a pinion 4, meshing with and driving a gear 5. The pinion and gear are shown as inclosed in a casing 6. The main shaft 7 of the machine is to be driven intermittently at the will of the operator, and this may be accomplished by any appropriately-controlled clutch devices. Those shown are as follows, Figs. 1, 2, 11, and 12: The shaft 7, lying within the hub of the wheel 5, has formed in it a longitudinal segmentary groove 8, in which fits a correspondingly-shaped part 9 of a locking key or clutch 10, that rocks in a bearing on a sleeve 11, surrounding a shaft. The outer face of the part 9 of the key is formed or cut so as to be coincident with the periphery of the shaft. At one or more points the bearing-hub of the wheel is formed with internal recesses 12. Fast on one end of the part 10 is a radially-projecting arm or tailpiece 13, to which one end of a coiled spring 13' is attached, the opposite end of the spring being secured to the sleeve 11, Fig. 11. The arm 13 is normally held by a stop 14 in such position that the wheel 5 revolves freely without actuating the shaft. The stop 14 is shown as a straight arm attached to the end of a rock-shaft 15, arranged at right angles to the shaft 7. From the opposite end of the shaft 15 projects a radial arm 16, connected by a link 17 with a treadle 18, hinged to the frame at 19. A spring 20, attached at one end to the stop-arm 14 and at the other end to the frame, serves to hold the parts in the normal position. (Indicated in Figs. 2 and 11.) When the operator depresses the treadle, the stop 14 is moved out of engagement with the arm 13, the spring 13' partially rotates the clutch-piece 10, and one of the angular edges of the part 9 thereof engages one of the recesses 12 in the hub of the wheel. The foot of the operator being removed from the treadle the shaft 7 will be rotated through one revolution, when the parts are restored to normal position by abutment of the arm 13 against the stop 14. On the movement of the shaft 7 the centrally-located crank 21 thereof actuates an arm or pitman 22, Figs. 1 and 5, jointed

to the rocking arm or lever B', the upper end of which is connected by a link b with the under side of the sliding head B. The connection between the crank and rocking arm 5 B' is composed of two pieces one sliding in the other and provided with a spring 23, which cushions the pressure of the sliding head on the abutments in the operation already described, and with a collar 24, which 10 positively connects the two parts on the return motion. When the sliding head B is started forward, the presser-plate G² is allowed to descend, and this may be conveniently accomplished as follows: A sprocket-wheel 25 on the rear end of the shaft 7 carries a drive-chain 25', running over a sprocket-wheel 26, having a double number of teeth and mounted in bearings, as shown in Fig. 1, at the right side of the machine. The shaft 15 27, to which the latter sprocket-wheel is fast, carries a double cam 28, the two portions of which are of corresponding contour and project, respectively, on opposite sides of the shaft. This sprocket-wheel and shaft will 20 make one half-revolution for each full revolution of the main shaft 7. The horizontal arm of a right-angle lever 29, Figs. 1 and 6, rocks loosely upon a shaft 30, and its downwardly-extending vertical arm carries a roller 25 that bears upon the sections of the double cam 28. At the angle of the lever 29 is jointed a rod 31, which passes upwardly through an aperture in the bed-plate and is hinged to the lever G, carrying a presser-plate G². The 30 coiled spring G³ is interposed between the bottom of the bed-plate and a collar on the rod 31. The reaction of the spring tends to move the rod downwardly. As seen in Fig. 1, the roller of the lever 29 is upon the highest point or edge of one of the sections of the cam 28. As the shaft 27 commences to revolve in the direction of the arrow the rod 31 will be permitted under the stress of its spring to move downwardly quickly until the presser- 35 plate G² bears upon the boards lying on the bed-plate, and when the half-revolution of the shaft 27 has been completed obviously the presser-plate will have been again raised to its normal position.

40 In the operation of doweling, the two boards having been completed, the operator withdraws them from between the dowel-holders D, and a cam 32, Figs. 1, 2, and 10, located near the rear end of the main shaft 7, acts 45 upon a roller 33 in the end of a horizontal arm 34, which is supported by an upright pivoted arm 35, mounted on a frame and the other end of which is connected to a radial arm 35', (indicated by dotted lines in Fig. 1,)

50 on the rear end of the rock-shaft E'. Keyed to this shaft, Figs. 8 and 9, is a radially-projecting arm 36, having a cross-head 37, in the ends of which are mounted two set-screws that bear, respectively, upon the two arms E 55 E', that actuate the sliding dowel-holder frames. Consequently the dowel-holders are moved to the right by a positive motion

into proper juxtaposition, Fig. 4, to the dowel-receptacles F F, and the plunger f' thereof being actuated dowels are ejected and forced 70 between the holders, as shown in Fig. 4. When this operation has been completed, the roller 33 passes from the high point of the cam 32, and under the stress of the springs B² the two arms E E are quickly retracted to 75 bring the dowel-holders into their normal central position. While the dowel-holders were in proper juxtaposition to the dowel-receptacles the cam 39 acted upon the roller 40, mounted on the pivoted upright arm or link 80 41, and moved to the right the horizontal arm 42, connected with the upper end of the arm 41. This arm slides in a bearing 43 in a bracket bolted to one of the uprights in the frame, and between said bearing and a collar 85 44, fast on the rod, is placed a coiled spring 45, that serves to return the rod to the left into normal position as the roller 41 runs upon the fall of the cam 39. Beyond the bearing 43 the rod is extended and passes through 90 the lower end of a radial arm 46, extending from the rock-shaft 30, having bearings in brackets mounted on the right-hand side of the frame. A collar 48 is applied fast to the rod outside of the arm 46, and between the 95 end of that arm and the bearing 43 is interposed a compressible coiled spring 49. As the rod moves to the right the arm 46 is yieldingly acted upon. On the rock-shaft are two upwardly-extending arms 50, which extend 100 into apertures 51, Figs. 1 and 7, of the respective heads of the reciprocating plungers f', which are mounted to slide in bearings in the right-hand end of the frame. The plungers are therefore moved to the left to eject 105 dowels from the receptacles F into the opposed dowel-holders D. The spring 49 is provided to cushion the action of the plungers in the event of any obstruction to the free discharge of the dowels from the receptacles. 110

Extending upwardly and outwardly from each dowel-receptacle are arms or brackets 52, formed with dowel-channels 53 in their upper faces, and the dowels Z, Fig. 4, descending by gravity through this channel fall 115 one upon another in the vertical dowel-receptacle F. In the upper ends of the brackets 52 is hinged a hopper, which is preferably of the construction shown in Figs. 13 to 17, inclusive—that is to say, it has an oblong receptacle having parallel sides 54, inwardly-inclined ends 55, and on each side of the longitudinal center of the hopper the bottom thereof is formed with converging portions 56 120 57. In rear or to the right of the pivotal axis 125 of the hopper and at the conjunction of the oppositely-inclined parts 56 57 the bottom of the hopper is cut away, forming a slot 58, which opens into a channel 59, formed in strips 60, attached to the bottom of the hopper, and 130 to each are applied the bearings 61, on which the hopper rocks. When the hopper is in the position shown in Fig. 13, the dowels, which fall through the slots 58, lie end to end in the

channels 59, and these channels communicate with the channels 53 in the brackets or arms 52, so that the dowels slide downwardly into the receptacles F, Fig. 4. Their passage, however, down through the channels 53 in the brackets 52 is controlled in the following manner: Mounted upon each bracket 52 is a block or part 62, in the upper ends of which a rock-shaft 63 has its bearings. A radial arm 64 on this rock-shaft is connected by a link 65 with the rocking arm or lever G. On each end of the rock-shaft 63 is a cross-head 66, in the opposite ends of which two feed-regulating plungers 67 68 work, coiled springs 69 being applied around them. These feed-plungers are in line with the channels 53 in the brackets 52 and work in guideways or apertures in the block 62, Figs. 1 and 13. As, therefore, the arm or lever G rises the lower feed-plunger 68, or that to the left, is raised and the other one, 67, is lowered, this condition being indicated in Fig. 13. The interval between the two feed-plungers is approximately equal to the length of the dowel, and consequently when the feed-plunger 67 descends it arrests or blocks the dowel above it, while the dowel immediately below it and which previously had been arrested by the feed-plunger 68 is allowed to slide downwardly into the dowel-receptacle F, Fig. 4. In this way the receptacles are kept supplied with dowels.

The dowel-hopper is manipulated as follows in order to insure a supply of dowels for the channel-ways 58 and 53. The hopper is pivoted at 61 in the upper ends of the arms or brackets 52, with the center of gravity materially to the right of the pivotal axis. A suitable number of dowels Z are placed in the hopper, and in the operation of the machine the following action occurs: The shaft 27, as before stated, is rotated through half a revolution during one revolution of the main shaft 7, and from the front end of the shaft 27 projects a radial arm 70, Fig. 1. From its end a cord or chain 71 extends to the hopper to the left of its axis of oscillation. During one half-revolution of the shaft 27 the left-hand end of the hopper is drawn downwardly into the position shown in Fig. 13 and on the next half-revolution it is allowed to rock into the position shown in Fig. 1. When in the position shown in Fig. 13, the dowels naturally fall to the front, as indicated, and when rocked back, as in Fig. 1, the dowels shift or slide to the right and in so doing they are by the action of inclined sides 56 57 caused to arrange themselves in line and fall through the slots 58 into the channels 59, from whence by gravity they descend into the continuations 53 of such channels, formed in the brackets 52. It is contemplated that when the rope or chain 71 rises the right-hand end of the hopper will rock downwardly without being specially weighted for that purpose, the weight of the bars 60, in which the channels 59 are formed, being suf-

ficient to produce this action. However, the same result may be accomplished by properly apportioning the relative length to the right of and to the left of the axis on which the hopper rocks, or, if desired, an adjustable weight 72 may be attached to the bottom of the hopper near its right-hand end.

We claim as our invention—

1. In a doweling-machine, the combination of a dowel-holder adapted to detachably hold a dowel, a feed-table upon which the boards to be doweled may be placed on opposite sides of the dowel-holder, means for pressing the edges of the boards together while the dowel enters them, and means for automatically placing a dowel in the holder after each operation.

2. In a doweling-machine, a feed-table to receive the boards, a dowel-holder adapted to detachably hold a dowel and free to move longitudinally of the table, means for pressing the edges of the boards together to cause the dowel to enter them, and means for automatically placing a dowel in the holder after each operation.

3. In a doweling-machine, the combination of a table or support for the boards, a dowel-holder mounted to move longitudinally of the table and adapted to detachably hold the dowel, means for pressing the edges of the boards together to cause the dowel to enter them, a dowel-receptacle, a dowel-hopper, means for automatically transferring dowels from the hopper to the receptacle and means for transferring a dowel from the receptacle to the holder after each operation.

4. In a doweling-machine, the combination of a feed table or support for the boards, a dowel-holder free to move longitudinally of the table, adapted to detachably hold a dowel and be moved out of the path of the boards, a movable board-pressing member on one side of the dowel-holder, an abutment on the other, a dowel-receptacle and means for automatically introducing a dowel into the holder after each operation.

5. In a doweling-machine, the combination of a dowel-holder comprising opposed members whose opposite edges are formed with convergent bevels and between the faces of which a dowel may be detachably held, a feed-table upon which the boards may be placed on opposite sides of the dowel-holder and means for pressing the edges of the boards together to cause them to engage the dowel and move the dowel-holder out of the way.

6. In a doweling-machine, the combination of a dowel-holder comprising opposite members whose opposite edges are formed with convergent bevels and between the faces of which a dowel may be clamped, springs which force the two faces of the dowel-holder together to clamp a dowel between them, a feed-table upon which the boards may be placed on opposite sides of the dowel-holder and means for pressing the edges of the boards to-

gether to engage the dowels and displace the members of the dowel-holder.

7. In a doweling-machine, the combination of a feed-table upon which the boards to be doweled may be placed, a dowel-holder mounted to slide or move longitudinally of the feed-table from its normal central position and constructed to removably hold a dowel and to be pressed by the edges of the board out of the way, a sliding head at one end of the feed-table and an abutment at the other between which two members the boards are pressed to cause their edges to engage the dowel and move the dowel-holder out of the way and means for automatically placing a dowel in the dowel-holder after each operation.

8. In a doweling-machine, the combination of a feed-table upon which the boards to be doweled may be placed, a dowel-holder mounted to slide or move longitudinally of the feed-table from its normal central position and constructed to removably hold a dowel and to be pressed by the edges of the boards out of the way, a sliding head at one end of the feed-table and an abutment at the other between which two members the boards are pressed to cause their edges to engage the dowel and move the dowel-holder out of the way, means, acting after the doweling of two boards, to move the dowel-holder to and from the abutment and means for supplying the holder with another dowel while the holder is adjacent the abutment.

35 9. In a doweling-machine, the combination of a feed-table, a sliding head mounted at one end of the feed-table, an abutment and dowel-receptacle located at the other end of the table, a dowel-holder constructed and adapted to removably hold a dowel and be moved out of the way by pressure of the edges of the boards, means, acting after the doweling of two boards, for moving the dowel-holder into operative relation with the dowel-receptacle, means for then ejecting a dowel from the receptacle and into the holder, and means for then returning the dowel-holder to its normal position.

10. In a doweling-machine, the combination of a feed-table, a sliding head mounted at one end of the feed-table, an abutment and dowel-receptacle located at the other end of the table, a dowel-holder constructed and adapted to removably hold a dowel and be moved out of the way by pressure of the edges of the boards, means, acting after the doweling of two boards, for moving the dowel-holder into operative relation with the dowel-receptacle, means for then ejecting a dowel from the receptacle into the holder, means for then returning the dowel-holder to its normal position, and means for automatically supplying the dowel-receptacle with dowels.

11. In a doweling-machine, the combination of a dowel-holder comprising opposed members whose opposite edges are formed with convergent bevels and between the faces of which a dowel may be detachably held, a feed-

table upon which the abutment may be placed on opposite sides of the dowel-holder, a presser bearing upon the boards and holding them flat upon the feed-table while their edges are being forced together and means for pressing the edges of the boards together to cause them to engage the dowel and move the dowel-holder out of the way.

12. In a doweling-machine, the combination of a dowel-holder comprising opposite members whose opposite edges are formed with convergent bevels and between the faces of which a dowel may be clamped, springs which force the two faces of the dowel-holder together to clamp a dowel between them, a feed-table upon which the boards may be placed on opposite sides of the dowel-holder, a presser bearing upon the boards and holding them flat upon the feed-table while their edges are being forced together and means for pressing the edges of the boards together to engage the dowels and displace the members of the dowel-holder.

13. In a doweling-machine, the combination of a feed-table upon which the boards to be doweled may be placed, a presser bearing upon the boards and holding them flat upon the feed-table while their edges are being forced together, a dowel-holder mounted to slide or move longitudinally of the feed-table from its normal central position and constructed to removably hold a dowel and to be pressed by the edges of the boards out of the way, a sliding head at one end of the feed-table and an abutment at the other between which two members the boards are pressed to cause their edges to engage the dowel and move the dowel-holder out of the way and means for automatically placing a dowel in the dowel-holder after each operation.

14. In a doweling-machine, the combination of a feed-table upon which the boards to be doweled may be placed, a presser bearing upon the boards and holding them flat upon the feed-table while their edges are being forced together, a dowel-holder mounted to slide or move longitudinally of the feed-table from its normal central position and constructed to removably hold a dowel and to be pressed by the edges of the boards out of the way, a sliding head at one end of the feed-table and an abutment at the other between which two members the boards are pressed to cause their edges to engage the dowel and move the dowel-holder out of the way, means, acting after the doweling of two boards, to move the dowel-holder to and from the abutment and means for supplying the holder with another dowel while the holder is adjacent the abutment.

15. In a doweling-machine, the combination of a feed-table, a presser bearing upon the boards and holding them flat upon the feed-table while their edges are being forced together, a sliding head mounted at one end of the feed-table, an abutment and dowel-receptacle located at the other end of the table, a dowel-holder constructed and adapted to

movably hold a dowel and be moved out of the way by pressure of the edges of the boards, means, acting after the doweling of two boards, for moving the dowel-holder into operative relation with the dowel-receptacle, means for then ejecting a dowel from the receptacle into the holder, and means for then returning the dowel-holder to its normal position.

16. In a doweling-machine, the combination of a feed-table, a presser bearing upon the boards and holding them flat upon the feed-table while their edges are being forced together, a sliding head mounted at one end of the feed-table, an abutment and dowel-receptacle located at the other end of the table, a dowel-holder constructed and adapted to removably hold a dowel and be moved out of the way by pressure of the edges of the boards, means, acting after the doweling of two boards, for moving the dowel-holder into operative relation with the dowel-receptacle, means for then ejecting a dowel from the receptacle into the holder, and means for then returning the dowel-holder to its normal position, and means for automatically supplying the dowel-receptacle with dowels.

17. In a doweling-machine, comprising a feed-table, a sliding plunger at one end thereof, an abutment and a dowel-receptacle at the other end thereof, a dowel-holder adapted to removably hold a dowel and be forced out of the way by the edges of the boards, a dowel-holder frame slidable or movable longitudinally of the table to and from the dowel-receptacle and a feed device for ejecting a dowel from the receptacle and delivering it to the dowel-holder, the combination of a continuously-driven driving-shaft, an intermittently-driven main shaft and mechanism for respectively operating the sliding head, the dowel-holder and the dowel-feed devices for the purposes herein set forth.

18. In a doweling-machine comprising a feed-table, a sliding plunger at one end thereof, an abutment and a dowel-receptacle at the other end thereof, a dowel-holder adapted to removably hold a dowel and be forced out of the way by the edges of the boards, a dowel-holder frame slidable or movable longitudinally of the table to and from the dowel-receptacle, a feed device for ejecting a dowel from the receptacle and delivering it to the dowel-holder and a presser-plate for holding boards against the table, the combination of a continuously-driven driving-shaft, an intermittently-driven main shaft and mechanism for respectively operating the sliding head, the dowel-holder and the dowel-feed devices for the purposes herein set forth and for raising and lowering the presser-plate.

19. In a doweling-machine comprising a feed-table, a sliding plunger at one end thereof, an abutment and a dowel-receptacle at the other end thereof, a dowel-holder adapted to removably hold a dowel and be forced out of the way by the edges of the boards, a dowel-

holder frame slidable or movable longitudinally of the table to and from the dowel-receptacle, a feed device for ejecting a dowel from the receptacle and delivering it to the dowel-holder, a dowel-hopper and means for automatically delivering dowels from the hopper to the dowel-receptacle, the combination of a continuously-driven driving-shaft, an intermittently-driven main shaft and mechanism for respectively operating the sliding head, the dowel-holder and the dowel-feed devices for the purposes herein set forth and for automatically transferring dowels from the hopper to the dowel-receptacle.

20. In a doweling-machine, the combination of a feed-table, a sliding head at one end thereof, an abutment at the other, a pair of dowel-holders independently movable longitudinally of the table and constructed and adapted to removably hold dowels and to be moved out of the way by the pressure of the edges of the boards and means for automatically supplying each holder with a dowel after each operation.

21. In a doweling-machine, the combination of a feed-table, a sliding head mounted at one end thereof, at the other end thereof an abutment and two dowel-receptacles, a pair of dowel-holders independently movable longitudinally of the table and each constructed to removably hold a dowel and be pressed out of the way by the edges of the boards, means, acting after the doweling of the two boards, for moving the two dowel-holders into operative relation to the respective dowel-receptacles, means for then transferring a dowel from each receptacle to its corresponding dowel-holder and means for returning the dowel-holders to their normal position.

22. In a doweling-machine, the combination of a feed-table, a sliding head at one end thereof, at the other end thereof an abutment and two dowel-receptacles, a pair of dowel-holders independently movable longitudinally of the table and each constructed to removably hold a dowel and be pressed out of the way by the edges of the boards, means, acting after the doweling of the two boards, for moving the two dowel-holders into operative relation to the respective dowel-receptacles, means for then transferring a dowel from each receptacle to its corresponding dowel-holder, means for returning the dowel-holders to their normal position and means for automatically supplying dowels to the dowel-receptacle.

23. In a doweling-machine, the combination of a feed-table, a presser-plate for holding the boards against the table while being doweled, a sliding head mounted at one end of the table, at the other end thereof an abutment and two dowel-receptacles, a pair of dowel-holders independently movable longitudinally of the table and each constructed to removably hold a dowel and be pressed out of the way by the edges of the boards, means, acting after the doweling of the two boards, for moving the

two dowel-holders into operative relation to the respective dowel-receptacles, means for then transferring a dowel from each receptacle to its corresponding dowel-holder and means for returning the dowel-holders to their normal position.

24. In a doweling-machine, the combination of a feed-table, a sliding head mounted at one end thereof and an abutment at the other, dowel-holders mounted at the front and rear edges of the table and constructed to slide independently of each other, toward the abutment end of the table, under the stress of the advancing board and each constructed to removably hold a dowel and be pressed out of the way by the edges of the board, dowel-receptacles at the abutment end of the table arranged respectively in line with the dowel-holders, means for positively moving the dowel-holders into operative relation to such receptacles, means for then delivering a dowel from each receptacle to its corresponding dowel-holder and means for returning the dowel-holders to their normal position.

25. 25. In a doweling-machine, the combination of a feed-table, a sliding head mounted at one end thereof and an abutment at the other, dowel-holders mounted at the front and rear edges of the table and constructed to slide independently of each other, toward the abutment end of the table, under the stress of the advancing board, and each constructed to removably hold a dowel and be pressed out of the way by the edges of the board, dowel-receptacles at the abutment end of the table arranged respectively in line with the dowel-holders, means for positively moving the dowel-holders into operative relation to such receptacles, means for then delivering a dowel from each receptacle to its corresponding dowel-holder, means for returning the dowel-holders to their normal position, a dowel-hopper and means for automatically feeding dowels from the hopper to the dowel-receptacles.

45. 26. In a doweling-machine, the combination with a feed table, sliding head, dowel-holder, and dowel-receptacle, of a part or bracket having a dowel-channel communicating with the receptacle, an oscillating dowel-hopper mounted at the upper end thereof and comprising a bottom with inclined convergent parts with a slot at the line of intersection thereof and a channeled piece located below the slot and registering with the dowel-chan-

nel before mentioned when the hopper is in 55 one of the positions into which it may be oscillated.

27. In a doweling-machine, the combination with a feed-table, sliding head, dowel-holder and dowel-receptacle, of a part or bracket having a dowel-channel communicating with the receptacle, an oscillating dowel-hopper mounted at the upper end thereof and comprising a bottom with inclined convergent parts with a slot at the line of intersection thereof, a 60 channeled piece located below the slot and registering with the dowel-channel before mentioned when the hopper is in one of the positions into which it may be oscillated, and means, acting upon the dowels in the last-named dowel-channel, for permitting them to slide one by one into the dowel-receptacle.

28. The combination with the dowel-receptacle, of a part or bracket, as 52, having therein an inclined dowel-channel opening to 75 the receptacle at its lower end, an oscillating hopper mounted at the upper end of said channel and comprising a bottom portion formed by the convergent parts with a slot at the intersection of said parts and in rear 80 of the axis of oscillation and a channeled piece arranged below the slots and communicating with the channel 52 when the hopper is in one of the positions into which it may be oscillated. 85

29. The combination with the dowel-receptacle of a part or bracket, as 52, having therein an inclined dowel-channel opening to the receptacle at its lower end, an oscillating hopper mounted at the upper end of said 90 channel and comprising a bottom portion formed by convergent parts with a slot at the intersection of said parts and in rear of the axis of oscillation, a channeled piece arranged below the slots and communicating 95 with the channel 52 when the hopper is in one of the positions into which it may be oscillated, and feed devices acting upon the dowels in the channel of part 52 to permit them to slide, one by one, into the dowel-receptacle. 100

In testimony whereof we have hereunto subscribed our names.
